UNITED STATES PATENT OFFICE.

AUGUST L. PALIS, OF UPLAND, CALIFORNIA.

ENVELOP-OPENER.

1,031,578.

Specification of Letters Patent.

Patented July 2, 1912.

Application filed August 11, 1911. Serial No. 643,530.

To all whom it may concern:

Be it known that I, AUGUST L. PALIS, of Upland, in the county of San Bernardino and State of California, have invented certain new and useful Improvements in Envelop-Openers; and I do hereby declare the following to be a full, clear, and exact description of the invention, such as will enable others skilled in the art to which it appertains to make and use the same.

The primary object of this invention is to provide a simple and highly efficient device for opening letters by cutting the envelope along or close to their edges and without danger of tearing either the envelope or their contents.

The invention will be hereinafter fully set forth and particularly pointed out in the claim.

20 In the accompanying drawings, Figure 1 is an elevation showing the parts out of working position. Fig. 2 is a view at right angles to Fig. 1. Fig. 3 is an enlarged section on lines 3—3, Fig. 2. Fig. 4 is a diagrammatic view showing the manner in which the device is employed.

Referring to the drawings, 1 designates a clip or holder which is preferably composed of metal of U-shape with its two spring arms 30 normally slightly divergent when the device is not in use, the free ends of the arms being bent outwardly at right angles to form two corresponding seats. Upon one of these seats is journaled a cutter 2 in the form of a disk having a beveled or knife-like edge, while upon the other seat is journaled a guide and support for the cutting disk, and this also is in form of a disk, 3, having a peripheral groove 4 to receive the knife 40 edge of the cutting disk. This groove is of such depth as to prevent the edge of the cutting disk from contacting with its inner wall, and yet this groove serves to guide the cutting disk and properly align the two

disks when in operation. These disks may 45 be journaled by any suitable means, but they preferably fit on unthreaded portions of screws 5 which enter threaded openings in the seats.

Normally the two disks occupy slightly 50 inclined positions, at an angle to each other, but when pressure is applied to the spring arms of the clip or holder the disks are brought together with the knife edge of the cutting disk fitting in the peripheral groove 55 of the guiding disk. In practice the edge of the envelope is placed between the two disks and is grasped between them when pressure is applied upon the spring arms, and by a relative movement between the envelope and 60 the device, the disks are caused to revolve on their journals and thereby effect a clear cut of the paper without tearing it at any point.

A device thus constructed is very 65 convenient, especially in handling large mails, and by means thereof envelopes may be readily and easily severed without danger of tearing them or their contents.

I claim as my invention:

The herein described device comprising a clip or holder of U-shape having its arms of spring metal and normally slightly divergent, the outer ends of said arms having seats at right angles thereto, and two disks 75 journaled on said seats, one disk having a knife edge, and the other disk having a peripheral groove to receive said knife edge, such groove being of such depth that the knife edge cannot engage its inner wall. 80

In testimony whereof, I have signed this specification in the presence of two subscribing witnesses.

AUGUST L. PALIS.
